UNITED STATES PATENT OFFICE.

JOHN SEROR, OF COHOES, NEW YORK, ASSIGNOR OF ONE-HALF TO
EDWARD C. DOYLE, OF SAME PLACE.

RAILWAY-RAIL-CLEANING MACHINE.

SPECIFICATION forming part of Letters Patent No. 444,675, dated January 13, 1891.

Application filed May 17, 1890. Serial No. 352,184. (No model.)

To all whom it may concern:

Be it known that I, JOHN SEROR, a citizen of the United States, residing at Cohoes, county of Albany, and State of New York, 5 have invented certain new and useful Improvements in a Railway-Rail-Cleaning Machine, of which the following is a specification.

My invention relates to such improvements; 10 and it consists of the novel construction and combination of parts hereinafter described, and subsequently claimed.

Reference may be had to the accompanying drawings and the letters of reference marked 15 thereon, which form a part of this specification.

Similar letters refer to similar parts in the several figures therein.

Figure 1 of the drawings is a bottom plan 20 view of a street-railway car with my improved device for cleaning the railway-rails attached, the middle portion of the car being broken away. Fig. 2 is a side elevation of the same. Fig. 3 is a vertical cross-section of a hanger 25 which supports the slide-bearing of a brush-shaft, taken on the broken line 3 3 in Fig. 1. Fig. 4 is a similar section of the double hanger which supports one end of the cogged-wheel shafts, taken on the broken line 4 4 in Fig. 1. Fig. 5 is a central longitudinal section of one 30 of the rotary brushes, showing the brush-shaft in section, with some of the wires removed from the hub-sleeves. Fig. 6 is a plan view of one of the hub-sleeves with the wires 35 removed. Fig. 7 is an end view of the sleeve, showing some of the wires inserted. Fig. 8 is a plan view of one of the wire staples detached from the hub-sleeve.

A is the car, which has end platforms A', 40 mounted upon the axles A², provided with fixed track-wheels A³.

Depending from the bottom of the car or platform are the hangers A⁴ and A⁵, which support the rotary shaft A⁶, having fixed 45 thereon the cogged wheel A⁷. Such shaft is connected at each end by a universal joint A⁸ with one end of a brush-shaft B. The other end of each brush-shaft is provided with a cylindrical brush B', and is supported by a 50 hanger B², depending from the bottom of the car, in a position such that the brushes ex-

tend diagonally across the track-rails, one across one rail and the other across the other rail. The position of the rails is indicated in Fig. 1 by the dotted lines B³. The cogged wheel A⁷ engages with the cogged wheel B⁴, 55 fixed upon shaft B⁵. The latter shaft has its bearings in the hangers A⁴ and B⁶ and is provided with the sprocket-wheel B⁷, fixed thereon. The sprocket-wheel is connected by the 60 sprocket-chain B⁸ with the sprocket-wheel B⁹, fixed upon one of the car-axles, which axle has the function of a driving or motor shaft, whereby a rotary movement is communicated from such axle to the brushes, the cogged 65 wheels being interposed to reverse the rotary movement and cause the brush-shafts to rotate in a direction opposite to that of the car-axles and force the obstructions to either side of the track. When the track is approximately 70 free from obstructions, and the brushes not needed, they can be raised from the rails by means of the levers C, fulcrumed in the hangers C', depending from the bottom of the car, one end C³ of each lever being movably 75 secured to a brush-shaft and the shaft being supported by a slide-bearing B¹⁰, movable vertically in the slideway B¹² in the hanger B². The other end C³ of each lever is linked to the hand-lever C⁴, fulcrumed at C⁵ upon the dash-board A⁸.

The hand-lever is provided with a stop-latch C⁶, fulcrumed at C⁷ upon the lever, and controlled by spring C⁸, adapted to hold the lever in the desired position by means of the nose 85 C⁹, passing through an aperture in the lever and into one of a plurality of apertures formed in the dash-board and adapted to receive it.

That part of the hanger A⁴ which supports shaft B⁵ is provided with a horizontally-elongated bearing-slot D, which permits of a sufficient lateral and horizontal movement of the shaft to withdraw the cogged wheel fixed thereon from engagement with the other cogged wheel. The required lateral movement is imparted to the shaft by means of the rock-shaft D', which is supported by the hangers D² and provided with the rock-lever D³, linked to the hand-lever, and the rock-lever D⁴, connected by link D⁵ with the vibratory end of the shaft B⁵. The levers C and D³ are connected pivotally with the link D⁵, 95 100

- which links them to the hand-lever and brings them within the convenient control of the car-driver when standing upon the platform. By pushing down upon the handle of the lever 5 the brushes are lifted from the rails, and at the same time the rock-levers disconnect the cogged wheels, leaving the brushes idle, thus saving them from wear when the condition of the track is such that their use is not required.
- 10 By raising the hand-lever the brushes are forced down upon the rails and the cogged wheels into engagement. The brushes are preferably formed in sections consisting of a plurality of metallic hub - sleeves H, each 15 sleeve having its shell provided with numerous perforations H', adapted to receive the wires forming the brush proper. The wires are preferably in the form of a staple H². The prongs are passed through the perforations 20 from the inside of the sleeve, so that the yoke H³ of the staple rests upon the inner surface of the sleeve between the perforations which receive its prongs. The several sleeves, thus 25 provided with any desired number of wires and arranged in any desired known form, are successively slid upon a supporting-shaft H⁴, adapted to fit the interior of the sleeves and bear firmly against the yoke of the wire staples, thereby securing them in a fixed position.
- 30 The brush-shaft is provided with a collar H⁵, which forms a bearing-stop for the sleeve first slid onto the shaft. The end of the shaft is screw-threaded, as shown, and after the desired number of sleeves have been placed upon the shaft they are forced into close engagement with each other by a nut H⁶, fitting the threaded end of the shaft, which is turned up to tightly clamp the sections between the 35 nut and collar. I am thus able to produce a brush made wholly of metal, and if the brush wears unevenly the sleeve-section having the damaged wires can be easily removed and a new section inserted, or the relative position 40 of the sections can be changed from time to time as desired, until all the wires are worn out.
- 45 The slide-bearing B¹⁰ is provided with trunnions B¹⁸, (indicated by dotted lines in Fig. 1,) 50 adapted to slide and turn in the slideway grooves B¹² in the hanger B².

I prefer to make use of one of the car-axles as the motor-shaft for driving the brushes, as

shown; but any known form of motor may be employed.

What I claim as new, and desire to secure by Letters Patent, is—

1. In a railway-rail-cleaning machine, the combination, with a brush-shaft, of a fixed bearing located near one end of such shaft, a 60 movable-adjustable bearing located near the other end, means, substantially as described, for adjustably moving such movable bearing, and gear connections between such shaft and a motor-shaft, substantially as described. 65

2. In a railway-rail-cleaning machine, the combination, with a shaft rotary in fixed bearings, a motor-shaft, and gear connections between such shafts, of a pair of brush-shafts respectively connected at one end by a universal joint to the ends of the driven shaft, movable bearings for the other ends of the brush-shafts, and means, substantially as described, for adjustably moving the movable ends of the brush-shafts. 70

3. In a railway-rail-cleaning machine, a shaft rotary in fixed bearings, a cogged wheel fixed on such shaft, a counter-shaft having a fixed bearing at one end and an adjustable bearing at the other end, a cogged wheel fixed 80 upon the counter-shaft and engageable with the other cogged wheel, a sprocket-wheel fixed upon the counter-shaft, a car-axle, a sprocket-wheel fixed upon the axle, and a sprocket-chain connecting such sprocket - wheels, in 85 combination with a brush-shaft connected at one end with the shaft rotary in fixed bearings by a universal joint, a movable bearing which supports the other end of the brush-shaft, an adjusting-lever movably connected at one end 90 with the brush-shaft, a fixed fulcrum located intermediately of the ends of the adjusting-lever, a rock-shaft and levers with connections for connecting one of the rock-levers with the laterally-movable ends of the counter-shaft, a 95 hand-lever fulcrumed upon a fixed support, and a link connection for connecting the hand-lever with the brush-adjusting lever and one of the rock-levers, substantially as described.

In testimony whereof I have hereunto set my hand this 13th day of May, 1890.

JOHN SEROR.
